STAPLE-SET PAINTBRUSH

Lawrence R. Schumann, Boston, Mass.

Application September 2, 1947, Serial No. 771,733

2 Claims. (Cl. 15—204)

1

This invention relates to paint brushes and more particularly to a paint brush in which individual, spaced tufts of bristles are set into the brush handle, preferably by stapling.

The art of staple setting bristles in tufts into brushes is, of course, well known and is extensively used in setting bristles in various types of brushes, such as sweeping and dusting brushes, tooth brushes, and the like, commonly used dry or in a semi-dry condition. In paint brushes, however, where liquid carrying and spreading properties are of primary consideration, stable setting, so far as I am aware, has never been employed.

The principal cost, aside from the workmanship which goes into this manufacture of a paint brush, is in the bristles. The working, or paint applying, portion of the bristles of a paint brush is confined, in proper use of the brush, to the lower portion of the bristles which must present a substantially uniform, compact mass or bundle to give the brush its spreading qualities. The remainder of the bristle length serves to add flexibility to the bristles and to hold paint by capillary action between the bristles.

In accordance with this invention, the desirable paint applying properties of a conventional rubber or plastic set brush may be retained in paint brushes in which individual tufts of bristles are set in the handle and improved paint carrying or holding properties obtained. Moreover, a brush made in accordance with this invention can be produced at a fraction of the cost of a comparable rubber set brush made according to accepted methods.

It is therefore an object of this invention to provide a paint brush in which the working ends of the bristles of the several, individual tufts are equally distributed in a substantially uniform mass or bundle of desired shape.

Another object of the invention is to provide a paint brush of the above character in which the tufts of bristles in the portion of their length above the working portion are separated in a manner to form a plurality of wells or reservoirs for the reception of paint giving the brush somewhat the effect of a fountain brush.

Another object of the invention is to provide a paint brush of the above character in which adjacent tufts are flattened somewhat or made elliptical in the same direction to form elongated spaces between adjacent rows of bristles and in which other tufts of bristles are flattened at right angles to the flattening of those in the rows to close the ends of the spaces to form the wells.

A further object of the invention is to provide a paint brush which is economical to manufacture because of the reduced number of bristles required and because it is subject to manufacture by automatic machinery.

With the above and other objects and advantages in view, the invention consists in the parts and combinations hereinafter set forth.

2

with the understanding that various changes may be made therein such as in the size and shape and the arrangement of parts without departing from the spirit of the invention.

5 In the accompanying drawings in which there is shown a preferred embodiment of the invention by way of illustration:

Figure 1 is a side elevational view of a paint brush made in accordance with the invention;

10 Figure 2 is a fragmental bottom plan view of the handle before setting the bristles therein;

Figure 3 is a fragmental side elevational view of the lower end of the handle;

Figure 4 is a fragmental edge elevational view of the lower end of the handle;

15 Figure 5 is a fragmental sectional view taken on the lines 5—5 of Figure 2 showing longitudinal arrangement and method of setting the bristle tufts;

20 Figure 6 is a fragmental sectional view taken on the line 6—6 of Figure 2 showing the transverse arrangement of the bristle tufts, and

Figure 7 is a cross sectional view of the bristle arrangement taken on the line 7—7 of Figure 6.

25 Referring first to Figures 1 through 4, there is shown a brush handle 1 of conventional shape for a flat brush of the type for applying paint, varnish, enamel lacquer, etc. The handle illustrated is shown by way of example and may take various accepted shapes according to the use to which the brush is to be put and may be formed of wood, molded plastic or other accepted materials.

30 Formed on the bottom face 2 of the handle are a series of parallel ribs 3 of rectangular cross section and preferably extending transversely across the lower face of the handle, as is best illustrated in Figure 2. The ends of ribs 3 should terminate short of the corresponding side faces of the handle. Ribs 3 will ordinarily extend

35 substantially perpendicular to the sides of the brush. They may, however, be oblique to the sides without departing from the scope of this invention.

40 Between adjacent ribs 3 the handle is provided with a row of equally spaced sockets 4 of a diameter appropriate to receive tightly a tuft of bristles. The sockets 4 are preferably spaced relatively close together and the end sockets of the rows are substantially tangential to the end faces of ribs 3.

45 The handle is also provided with a row of sockets 5 outside the rib at each end of the row thereof and aligned with the outer vertical face of the ribs. In addition, a socket 6 is provided at opposite ends of each rib, as shown in Figure 2.

50 As stated, the sockets 4, 5 and 6 are of a diameter to receive tightly a tuft of the desired number of bristles. Preferably the width of the ribs 3, the spacing therebetween and the diameter of the sockets 4, 5 and 6 are substantially equal so that the cylindrical walls of the sockets lie tangential to the vertical faces of the ribs as best seen in Figures 5 and 6.

55 60

As shown in Figures 5 and 6, the bristles are staple set in tufts in the sockets 4, 5 and 6. This may be done in usual manner and the particular method of stapling forms no part of the present invention. For instance, the staple setting may be accomplished by placing a U-shaped staple, such as indicated at 7 in Figure 6, about the mid portion of a bundle of aligned bristles (or in certain cases adjacent the butt end of a bundle of bristles), bending the bundle about the staple to form a tuft 8, setting the tuft in the socket, and driving the staple into the bottom of the socket. The number of bristles in each tuft bundle is measured in order that the aforementioned tight fit of the tuft in the socket may be obtained. Then it will be found that the bristles of each tuft will fan outwardly somewhat from the rim of the socket to meet bristles of adjacent tufts a distance down from the lower face of the handle depending principally upon the spacing between adjacent sockets.

Because of the substantially tangential position of the sockets 4 and 5 in respect to the ribs 3, the vertical walls of the ribs engage the tufts extending from those sockets for a short distance from the rims of sockets 4 and 5. The tufts are thereby flattened to an essentially elliptical shape with the long axis of the tuft parallel to the faces of the ribs. The bristles of adjacent tufts 8A in the same row of tufts will come together relatively close to the face 2 of the brush handle, as is indicated by intersection 9 in Figure 6, because of the elliptical shape to give a continuous, uniform mass of bristles along any one row over the major portion of the length of the bristles. Similarly the tufts 8B and 8C are flattened to form a continuous mass of bristles along the outer surface of the brush.

On the other hand, the flattening of the tufts by the ribs cause the bristles in adjacent rows to come together at a greater distance from the face 2 of the brush, as is illustrated in Figure 5 by reference numeral 10. Between adjacent rows of tufts there will, consequently, be a series of wells or reservoirs 11 near the face of the brush and under each of the ribs 3. Wells or reservoirs 11 will be essentially triangular in vertical cross section and will extend for the full length of the ribs 3 across the face 2 of the brush. The ends of the reservoirs 11 at opposite sides of the brush are closed by tufts 8C at the end of the brush.

In practice it will usually be found that the reservoir 11 will extend downward from one to two-thirds of the distance from the face 2 of the handle to the ends of the bristles. When the brush is dipped, paint will flow into the reservoirs and will drain therefrom as the paint is "squeezed" from between the lower ends of the bristles in use of the brush. Thus the brush operates somewhat in the manner of the usual fountain brush. The lower third of the bristles or working ends form a substantially uniformly compact bundle to spread the paint efficiently. Since usually a brush is discarded after five or ten percent of the bristle length is worn away, the brush will function normally during its average life. In other words, the brush will serve its normal useful life long before the bristles ends have worn sufficiently to open up the wells or reservoirs by bristle end destruction.

While staple setting is disclosed herein as a simple and economical method of securing the bristles in the handle, it is obvious that other known methods may be employed, such as ce-

menting. In the case of plastic handles suitable plastic cements are employed for setting the bristles in preference to stapling because of the nature of the handle material. Again, with appropriate plastic handles and bristles, high frequency or induction heating may be employed for setting the bristles.

From the above it will be seen that the invention provides a paint brush in which the working ends of the bristles are arranged in a compact bundle to give desirable paint applying and spreading qualities to the brush. Moreover, the arrangement of the tufts of bristles provides reservoirs to hold paint and provides improved paint carrying properties. In addition, and while providing the above desirable characteristics, the invention provides substantial economies in manufacture by the use of less bristle and by lending itself to manufacture by automatic machinery of well known design.

I claim:

1. A paint brush comprising a handle having a face for the reception of bristles, a series of ribs on the face substantially perpendicular to the sides of the handle, said ribs terminating short of the edges of the face, there being a plurality of sockets in the face between adjacent ribs and tangent to the ribs, the outermost of said sockets having their outer surfaces substantially even with the ends of the ribs, there being other sockets in the face at the ends of the ribs and tangent thereto, there being still other sockets tangent to the ribs at the end of the brush, and tufts of bristles staple set in each of the sockets, said ribs separating rows of tufts and flattening the tufts in contact therewith to bring adjacent tufts in contact with each other close to said ribs and form substantially enclosed reservoirs for holding adjacent the upper portions of the bristles into a substantially uniform bundle.

2. A paint brush comprising a handle having a face for the reception of bristles, a series of ribs on the face, said ribs being spaced apart a distance substantially equal to their width, there being a plurality of closely spaced sockets between the ribs having a diameter substantially equal to the spacing between the ribs, there being other sockets tangent to the ends of the ribs, still other sockets tangent to the outer surfaces of the end ribs, and tufts of bristles staple set in the sockets, said ribs separating rows of tufts and flattening the tufts in contact therewith to bring adjacent tufts in contact with each other close to said ribs and form substantially enclosed reservoirs for holding paint adjacent the upper portions of the bristles and form the lower portions of the bristles into a substantially uniform bundle.

LAWRENCE R. SCHUMANN.
